METHOD OF PROCESSING PAPER

Ira C. Cowie, Norristown, and Jasper H. Purcell, Conshohocken, Pa., assignors to Glassine Paper Company, West Conshohocken, Pa., a corporation of Delaware

Application October 26, 1946, Serial No. 705,902

9 Claims. (Cl. 92—68)

1

This invention relates to a method and apparatus for processing paper, and in particular to such method and apparatus for enabling the simultaneous super calendering of a plurality of sheets of paper to produce finished sheets with dissimilar surfaced characteristics.

Commercial practices, presently followed, for the production of glassine, or other hard surfaced papers, involve the treatment of the sheets in such a manner that both surfaces thereof have the same characteristics. This is normally accomplished by passing individual sheets through a super calender. The density of the sheets is increased, and both surfaces are glazed and polished to the same extent. The finished product is of high quality and finds many uses, but is costly. This high cost bars such paper from many other uses, for which it would otherwise be selected. For many of such latter uses, one glazed surface, plus proper body characteristics, would meet all requirements. Up to the present, however, the trade has accepted as a fact, that the art of producing glassine, or grease proof papers, has precluded the furnishing of such papers having dissimilar surface preparations. In addition, the trade has also accepted, as a fact, that individual sheets of glassine and grease proof paper, having both of their faces similarly finished, were all that could be obtained for laminating into multiple ply constructions. Hence, considerable effort had to be expended in determining how to secure hard polished faces together.

Our contribution to the art enables the application of dissimilar surface properties to the opposite surfaces of a single sheet of glassine, or grease proof, paper. This is accomplished, however, without detracting from the desirable body characteristics of such papers as heretofore known in the art. In addition, dissimilar surface characteristics can be imparted to two sheets simultaneously with equipment of comparable cost to that heretofore required for imparting identical surfaces to one single sheet. Obviously, then, the cost of super calendering the paper of our invention is materially reduced from that of the prior art practice. Reduction of the cost factor opens up many more uses for this type of paper. In addition, the dissimilar surface aspects of our new paper render it highly desirable for a number of other uses.

As examples of new applications where our paper would be particularly desirable the first is where it is desired to keep slippage in handling down to a minimum. This can be accomplished

through contact with the unpolished surface of the sheet. Individual fruit wrapping can be enhanced by the use of this paper. The wrappers can be printed on the polished outer surface, thus improving sales appeal, while retaining the protection now offered by other papers, yet with a reduction in cost. Also, many bags can be made cheaper, when intended for uses where glassine surface characteristics are essential on only one side of the wrapper. Finally, a lamination of juxtaposed plies can be produced at a lower cost and in a more effective manner.

Considering the manner in which our new treatment of paper is carried out, one might think that the result we were seeking could be accomplished merely by passing two superimposed sheets through a common super calender. Such will not work, for where two sheets are sandwiched together, and run along through the common super calender, as if the sandwich were one single sheet, various defects arise. The most common defect results from the generation of moisture vapor from the drying of the sheets. This moisture vapor forms into bubbles which ride between the sheets directly in front of the calender nip. Each of these bubbles acts like a hard marble between the two sheets distorting, or distending, them. Then as the distorted, or distended, sheets run into the nip at least one of them is cut. Such cuts run with the travel of the sheet, and continue until the bubbles causing them dissipate in some manner. These cuts, of course, render the cut sheet worthless. Even though no cut results from the presence of the bubbles, a streak occurs which prevents proper super calendering of the sheets, with the result that decidedly inferior paper is produced. This happens so commonly that such a process could not be called satisfactory.

We have discovered, however, that there is a satisfactory way to run two or more sheets through a somewhat modified super calender, all at the same time. First, it is essential that the sheets must be separated before they enter the super calender, and that while separated, they must pass over a series of spreader boards in order to have any deficiencies and inequalities in the paper worked out before the sheets enter the stack. Next, the sheets must be kept apart as they go into each nip of the stack so that they will not come together until the exact instant that they reach the nip. Thus, the contact of the sheets, and the action of the calender stack on them, only takes place for the short distance where they pass between adjacent

3

rollers. The separation of the sheets coming out of the nip is not as critical as the maintaining of them apart until the exact instant that they come together on going into the nip. Nevertheless, the sheets should be separated and maintained apart for a sufficient length of time, to enable air to get at them before they go back into the next nip.

We have found that the performance of this method, by the employment of a modified calender stack to carry it out, wherein the sheets are separated and brought together again all the way down through the calender stack, imparts the treatment to the paper which is needed to give it the characteristics we were seeking. The outer face of each sheet is ironed to a good glaze, and polished, whereas the inner faces though smooth, will be unpolished.

Two sheets, each with a glaze on its outer face, and even additional intermediate sheets when a glazed face is not needed, can be treated through the method of our invention, at the same speed as has heretofore been employed for the treatment of a single sheet with both faces glazed. Furthermore, the apparatus, though modified is not particularly complicated over that previously used for single sheet production. Obviously, then, considerable economy is introduced into the production of sheet material in accordance with our invention. Its single sheet use is thus widely enhanced over the prior art material as above pointed out. Furthermore, the new material is excellent for laminating, since the fibres on the unpolished surfaces still retain some of their original roundness, and hence furnish increased securing surface. Transparency, if required, is not impaired, for the laminating cement, more transparent than the paper itself, fills in the unevennesses in the surfaces, while at the same time securing those surfaces together. Here also the economy of producing the individual sheets is multiplied by the number of sheets secured together, while at the same time a better laminated sandwich results.

If the finished sheets are to be used individually, or if their intended use has not been determined at the time they come off the calender, they can of course be wound up on separate rewind rolls. If, however, it is desired to immediately laminate the sheets they can be led right from the calender into the laminator, with consequent elimination of any intermediate handling. A third alternative would be to wind the sheets direct from the calender on to a single rewind roll, from whence a single rewinding would produce two sheets ready for use, rather than a single one.

If the apparatus of our invention be considered as a sort of a single super calender, then we accomplish more with one super calender at one time, than could previously be done by two or more super calenders, depending upon the number of sheets employed, or than could be done in twice the time with one super calender. Hence, the labor cost involved in producing the same amount of paper ready to be laminated is cut proportionally. Also, if the paper is led right into a laminator, the labor involved in handling the paper between the super calender and the laminator can be eliminated if desired. Another saving is in the wear and tear on the calender rolls, for obviously there is no more wear on calender rolls when several sheets are passed between them, than there is when only one is employed. Hence, the re-finishing of the calender

4

rolls is likewise cut in proportion to the number of sheets run through the calender stack. Finally, it can be readily appreciated that the production of a calender, with respect to material to be laminated, is multiplied by the process and apparatus of our invention.

It is accordingly an object of our invention to impart dissimilar surface characteristics to sheets of paper.

10 It is another object of our invention to provide for the imparting of dissimilar surface characteristics to sheets of glassine and grease proof paper.

Another object of our invention is to provide 15 a new process and apparatus for super calendering paper.

Another object of our invention is to produce a more economical paper of the glassine and 20 grease proof type.

Another object of our invention is to provide 25 a method and apparatus for multiplying the speed of finishing paper of the glassine and grease proof type.

Still another object of our invention is to provide 30 a method for improving the adhesive engaging characteristics of a face of fibrous sheet material.

Other objects of our invention are to reduce 35 labor costs in the production of paper of the glassine and greaseproof type; to extend the life of expendable parts of the apparatus employed, to provide a novel super calender-laminator combination and to reduce the cost of handling paper of the glassine and grease proof type.

Further and more detailed objects of the invention will become obvious to those skilled in the art, from a consideration of the following description taken in conjunction with the accompanying drawing, in which:

40 Figure 1 is a diagrammatic elevation of the super calendering mechanism of our invention, and for carrying out the process thereof, and

Figure 2 is a diagrammatic end elevation of an illustrative form of laminating mechanism, 45 operable in conjunction with the mechanism of Figure 1.

Figure 3 is a diagrammatic elevation of a 50 rewind roll and a fragment of our super calender, illustrating the rewinding of a plurality of sheets on a single re-wind roll.

Our invention will be described from the point of view of processing papers of the glassine type. It is, of course, understood that our method and apparatus could be employed with and performed upon other papers which respond in similar fashion to the treatment accorded glassine paper, as described herein. Hence, the reference to glassine is to be considered as in the illustrative and not the limiting sense.

When two sheets of suitable paper are introduced into our super calender each emerges with only one glazed and polished face, as against conventional glassine paper, which has both faces glazed and polished, but it is believed that material so super calendered falls generally within the accepted definitions of glassine. If intermediate sheets are employed they will not have either face glazed or polished, but their density will be increased by the super calendering and they will be effective for a variety of uses including lamination. In the accompanying drawing our invention is illustrated from the point of view of processing merely two sheets of paper. The supply rolls for the same, 1 and 2, as shown in 55 Figure 1 are of grease-proof paper which has

already been wetted or hydrated, ready to be passed into the super calender. The axles 3 and 4 of the rolls 1 and 2 are, suitably, and preferably, adjustably mounted in bearing hangers carried by and extending from the main frame of the super calender. The sheet 5 coming from the roll 1, as shown, passes over and in contact with the sheet 6 from the roll 2, and the sheets 5 and 6 travel together until they pass the idler roller 7. From this point on, the sheets are separated and pass over several sets or pairs of spreader boards 8-9 and 10-11, which thus carry the sheets in separated relationship across the top of the super calender stack. As the sheets are led down in back of the stack, they are passed over another pair of spreader boards 12 and 13, before going into the first nip 14.

For proper performance of our method we have found that the interposition of several spreader boards acting on each sheet in advance of the first nip is of extreme importance. The function of such boards eliminate any inequalities which may exist in the sheets passing thereover. These boards have their faces which engage the sheets inclined upwardly from each end towards their longitudinal center. The upward projection of the common spreader board at its center is usually about $\frac{1}{8}$ ". The incline of the boards downwards from the center tends to force the paper passing thereover outwardly from the center of the sheet toward the edges, spreading any wrinkles from the center out to the edges. The spreader boards also equalize any other deficiencies which may exist in the paper and put it under uniform tension throughout its width. This also eliminates any tendency of the paper to jerk as it moves forward. Obviously where two or more sheets are to pass through a series of nips together, it is desirable that extreme uniformity be imparted to all of them before they enter the first nip.

The location of the spreader boards 12 and 13 with respect to each other, and with respect to the nip 14, is also of particular importance, for, as already pointed out, it is a critical characteristic of our invention that the sheets such as 5 and 6 be kept apart until they meet right in the nip. Normally, the angle at which the sheets come together as they enter the nip should be 30° or more. The location of spreader boards, 12 and 13, this close to the nip, adjustable to vary the angle between the sheets, is also of prime importance, since it is most desirable to have the sheets extremely uniform, in all respects, when they come into the first nip of the super calender.

Rather than describe each roller of our super calender, in detail, we have indicated by arrows the direction in which they travel, and have shown by the letters S and P, respectively, whether the particular roller is a steel one, or a paper one. The reasons for providing the rollers of the material shown, and in the relationships indicated, are well known in the art, and it is not believed necessary to describe the function of each of them in detail. We will thus confine ourselves to identifying those rollers at the respective nips.

The nip 14 is formed by the rollers 15 and 16, which tend to come together at the point 14, and would do so save for the sheets of paper interposed therebetween. As indicated, the roller 15 is steel and the roller 16 is paper. The contact of the sheets 5 and 6 is only slightly greater than the distance required for them to pass in and out of, the nip 14. During this time, not

only are the sheets subject to the pressure of the stack, but the outer face of the sheet 6 is acted upon by the steel roller 15, while the outer face of the sheet 5 is acted upon by the paper roller 16. The inner faces of the sheets engage each other, so act against each other to provide a smoothing effect. The sheets 5 and 6 are separated as they leave the nip 14 and pass over the fly rolls 17 and 18, which are set apart at a convenient distance to properly separate the sheets and to guide them to their next position. Either or both, of the fly rolls 17 and 18 may be adjustable. They are carried by suitable hangers on the frame of the super calender.

On leaving the fly rolls 17 and 18, the sheets 5 and 6 are directed downward to adjacent the next nip 19 where the sheet 6 passes around the large fly roll 20, while sheet 5 passes around an adjustable fly roll 21. These fly rolls, like those previously referred to, are carried on the main frame of the super calender, and the adjustment of the roller 21 provides for whatever adjustment is necessary in the angle between the sheets 5 and 6, as they come in to the nip 19. In this nip the outer face of the sheet 5 is again engaged by a paper roll 22, while the outer face of sheet 6 is engaged by a steel roll 23. On leaving the nip 19 the sheet 5 passes well out to travel over the fixed fly roll 24, while the sheet 6 shortly engages the adjustable fly roll 25, and quickly goes back, at the proper angle with respect to the sheet 5, into the next nip 26, where the sheets again meet. On leaving the nip 26, the sheet 6 is the one to be carried out the greater distance, being passed over the fixed fly roll 27, while the sheet 5 passes over the adjustable fly roll 28, and turns quickly back into the next nip 29, when it again meets the sheet 6, at the proper angle, but this time between a pair of paper rolls 30 and 31.

From here on down, the previous conditions are reversed, since the sheet 6, after leaving the nip 29, passes over the adjustable fly roll 32 and into the nip 33, where its outer face is engaged by the paper roll 31, rather than by steel rolls, as heretofore. The sheet 5 passes out around the fixed fly roll 34 and into the nip 33, where it meets the sheet 6 at the appropriate angle and where its outer surface is engaged by the lower steel roll 35. Again, as the sheets come out of this nip, they pass over a pair of fly rolls 36 and 37, at least one of which is adjustable, with the combination of the location and adjustment of the fly rolls serving to assure the appropriate setting of the angle at which the sheets approach each other, on going into the next nip.

The upper roll of the next nip 38 is a steel one 39, while the lower one 40 is of paper. From the nip 38 the sheets make their final pass over the separate fly rolls 41 and 42, and go into their last nip 43, between the paper roller 40 and a large steel roll 44. Again the sheets meet at the appropriate angle as they come into the nip where they are acted upon by the full weight of the stack, with the paper roll 40 engaging the outer face of the sheet 6 and the steel roll 44, the outer face of the sheet 5. Though two sheets are thus passed through our modified super calender stack, it is to be noted that their travel is at substantially the same speed as has heretofore been employed in the super calendering of single sheets.

As they leave the nip 43, the sheets 5 and 6 are super calendered in the manner contemplated by our invention and are thus ready to be put

to any of the uses to which single sheets are adaptable, store, ready for laminating, or may be passed directly into a laminator, as the case may be. In the illustration of Figure 1, the sheets 5 and 6 are shown as being wound up on individual rewind rolls 45 and 46. This is the common practice, for then the paper can be put to any use desired. If the paper is to be printed upon, the glazed side should, of course, be used, while if two sheets are to be introduced into a laminator, it will be necessary to make sure that the faces to be brought together with the intermediate film of adhesive, are the inner, unpolished ones. The difference between the faces can be easily determined, since the glaze and polish on the outer surfaces is quite noticeably different from the mere smooth finish given to the inner surfaces. In spite of this smooth finish, however, the fact remains that the fibers on the inner faces are not crushed into the flattened form, the way they would be were a real glaze and polish imparted to them. Nevertheless, the body of the paper has been compressed in the super calendering, so that its density is increased and the smooth surface given to the inner face is of sufficient hardness, that the desirable moisture, vapor, and grease-proof characteristics are incorporated in the paper.

In Figure 2, we have illustrated a manner in which further savings can be effected by passing the sheets 5 and 6, on leaving the bottom pair of rollers 40 and 44 of the calender stack, directly into a laminator. Sheet 5 runs directly from the last nip 43 to the combining roll 47 of the laminator. Sheet 5 runs directly from the last nip 43 to the combining roll 47 of the laminator, while sheet 6 passes up over a waxing roll 48, where its under surface receives a coating of a suitable adhesive. Even spreading of this adhesive is assured by passing the sheet 6 over an additional spreader roller 49 from whence the sheet runs to a combining roll 47, when it is secured to the sheet 5 by means of its coating of adhesive. From the joining position 50, the sheets hug the surface of the combining roller 47, for a substantial arc thereof, and then pass around a substantial portion of the periphery of the roller 51. From the roller 51 the finished laminated sheet is rolled up on the rewind roll 57. No attempt has been made to show conventional details of a laminator, for it is believed that one skilled in the art could supply the same upon being provided with a diagrammatic showing of Figure 2.

In Figure 3 we have illustrated another manner of winding up the treated sheets as they come from the bottom of the super calender. The bottom rolls 40 and 44 of the super calender are the same as heretofore described, but we have illustrated three sheets, 5, 6 and 53 passing into the last nip of the same, rather than the two previously shown. Instead of separating these sheets, as they leave the nip, for separate rewinding, they are here all wound up together on a single rewind roll 54. Of course, the footage wound on such a roll would be less than would be the case were a single sheet being wound up, unless the roll were to be much larger than normal. This winding is of particular advantage when the paper is to be laminated since a composite rewind roll, such as 54, can be moved to the laminator, rather than a plurality of individual rolls, as would otherwise be necessary. This composite re-winding could, of course, be done as well with two sheets as with three, or, conversely, with a larger number.

Though we have not gone into detail to show precisely how one or more intermediate sheets of fibrous material could be carried along through our improved super calender, and be treated in accordance with the method of our invention, it is believed that one skilled in the art, following the above teaching, could determine how to do it and what the results would be. It would need to be kept in mind, first, that the initial spreading of each sheet must be fully carried out; next, that the angle by which the sheets approach the nip would have to be the appropriate one, considering the nature and condition of the material being fed thereto, and also that a separation of the sheets, as they travel from one nip to the next should be effected. Only the two outside sheets would have faces which are glazed and polished, the intermediate sheet, or sheets, having both faces finished merely to a smoothness comparable to that imparted to the inside faces of the outer sheets. Thus, care would need to be taken in selecting the proper sheet, and proper face for the use to which the paper was to be put.

It is believed that various changes in carrying out our process, and in the construction we have disclosed, may be made while still embodying the invention and without departing from the scope thereof. It is thus intended that all matter contained in the above description, or shown in the accompanying drawing, is to be interpreted as illustrative and not in a limiting sense.

Having described our invention what we claim as new and desire to secure by Letters Patent is:

1. The improvement in the art of super calendering sheets of hydrated fibrous material which comprises, directing a plurality of separated sheets of said material toward each other at an angle to meet at substantially a line contact, pressing said sheets together at substantially said line of contact while ironing the outer surfaces thereof, releasing said pressure by separating said sheets and feeding them away from said line of contact, maintaining said sheets in said separated relation while transporting them with both faces of each thereof exposed to the air, directing said sheets toward each other again at an angle to meet at substantially a second line contact, and pressing said sheets together and ironing the outer surfaces thereof at substantially said second line contact.

2. The improvement in the art of super calendering sheets of hydrated fibrous material which comprises, directing two spaced sheets of said material toward each other at an angle to meet at substantially a line contact, pressing said sheets together at substantially said line of contact while ironing the outer surfaces thereof, releasing said pressure by separating said sheets and feeding them away from said line of contact, maintaining said sheets in said separated relation while transporting them with both faces of each thereof exposed to the air, directing said sheets toward each other again at an angle to meet at substantially a second line contact, and pressing said sheets together and ironing the outer surfaces thereof at substantially said second line contact.

3. The improvement in the art of super calendering sheets of hydrated fibrous material which comprises, directing two spaced sheets of said material toward each other at an angle to meet at substantially a line contact, pressing said sheets together at substantially said line of contact while ironing the outer surfaces thereof, releasing said pressure by separating said sheets

and feeding them away from said line of contact, maintaining said sheets in said separated relation while transporting them with both faces of each thereof exposed to the air, directing said sheets toward each other again at an angle to meet at substantially a second line contact, pressing said sheets together and ironing the outer surfaces thereof at said second line contact, and releasing said pressure and separating said sheets again to expose both sides of each thereof to the air as they leave said second line contact.

4. The improvement in the art of super calendering sheets of hydrated fibrous material which comprises, spreading separated sheets of said material laterally to render each of them uniform throughout their width, directing said sheets toward each other to meet at an angle at substantially a line contact, pressing said sheets together at substantially said line of contact while ironing the outer surfaces thereof, releasing said pressure by separating said sheets and feeding them away from said line of contact, maintaining said sheets in said separated relation while transporting them with both faces of each thereof exposed to the air, directing said sheets toward each other again at an angle to meet at substantially a second line contact, and pressing said sheets together and ironing the outer surfaces thereof at substantially said second line contact.

5. The improvement in the art of super calendering sheets of hydrated fibrous material which comprises, directing a plurality of separated sheets of said material toward each other to meet at substantially a nip of a super calender stack, pressing and ironing said sheets together in said nip, feeding said sheets past said nip and separating said sheets again to expose both faces of each thereof to the air, transporting said sheets with said faces so exposed, bringing said sheets together again to meet substantially at another nip of said super calender stack, and pressing said sheets together and ironing the outer surfaces thereof in said other nip.

6. The improvement in the art of super calendering sheets of hydrated fibrous material which comprises, directing a plurality of sheets of said material toward each other to meet at substantially a nip of a super calender stack, pressing and ironing said sheets together in said nip, feeding said sheets past said nip and separating said sheets again to expose both faces of each thereof to the air, transporting said sheets with said faces so exposed, bringing said sheets together again to meet substantially at another nip of said calender stack, pressing said sheets together and ironing the outer surfaces thereof in said other nip, and releasing said pressure and separating said sheets again to expose both faces of each thereof to the air as they leave said other nip.

7. The method of super calendering a plurality of sheets of hydrated fibrous material simultaneously which comprises, subjecting a plurality of sheets of such material to a series of similar pressing and ironing operations, each of said

series of operations comprising directing said sheets toward each other to meet at substantially a line contact while transporting said sheets with both faces of each thereof exposed to the air, pressing said sheets together at substantially said line of contact while ironing the outer exposed faces thereof, releasing said pressure from said sheets by feeding said sheets past said pressure station, separating said sheets again after release of said pressure and directing said sheets into position for commencement of the next of said series of similar operations.

8. The method as in claim 7 wherein a part of said series of pressing and ironing operations is performed with a rigid member on one side of said sheets and resilient member opposed thereto on the other side of said sheets, and another part of said series is performed with said rigid and resilient members in reversed relation.

15 9. The method of super calendering a plurality of sheets of hydrated fibrous sheet material simultaneously which comprises, subjecting said sheets to a series of similar pressing and ironing operations in the nips of a super calender stack, one of 20 said similar operations comprising transporting said sheets in separated relation with both faces of each thereof exposed to the air, directing said separated sheets toward each other to meet substantially at a nip of a super calender stack, pressing 25 said sheets together and ironing the outer surfaces thereof while passing said sheets through said nip in superposed relation, releasing said pressure by feeding said sheets past said nip, separating said sheets again as they leave said 30 nip to expose both sides of each of said sheets to the air and transporting said separated sheets into position for introduction into the next nip in said stack.
